UNITED STATES PATENT OFFICE.

RILEY A. STUBBS, OF GREENVILLE, OHIO, ASSIGNOR OF ONE-HALF TO
JOSEPH R. TURNER, OF SAME PLACE.

SEPARATOR.

SPECIFICATION forming part of Letters Patent No. 499,262, dated June 13, 1893.

Application filed September 5, 1891. Serial No. 404,839. (No model.)

To all whom it may concern:

Be it known that I, RILEY A. STUBBS, a citizen of the United States, and a resident of the town of Greenville, in the county of Darke 5 and State of Ohio, have invented certain new and useful Improvements in Separators, of which the following is a specification.

The several features of my invention and the various advantages resulting from their 10 use, conjointly or otherwise, will be apparent from the following description and claims.

In the accompanying drawings, making a part of this specification and to which reference is hereby made, Figure 1 is a top view 15 of a machine embodying my invention. Fig. 2^a is a view of the under side of the cover or top member of the machine, and showing the distributers and the mechanism for operating them. Fig. 2^b is a detail side view, 20 and Fig. 2^c is a top view of one of the distributers shown in Fig. 2^a. Figs. 2^b and 2^c are on an enlarged scale. Fig. 3 is a side elevation of the said machine. Fig. 4 is a vertical central section of the said machine 25 showing the various parts in position. Fig. 5^a is a plan view of one of the disk screens. Fig. 5^b is a plan view of one segment of disk screen. Fig. 5^c is a side elevation of one arm of said segment. Fig. 5^d is an end elevation 30 of one arm of segment. Fig. 6 is a bottom view of a skeleton wheel frame, employed at one location in my machine, to carry a set of distributers, the distributers not being shown. Fig. 7 is a top view of a disk screen prefer- 35 ably employed as the second one of the series belonging to my machine and carrying a collecting spiral. Fig. 8 is the floor of the machine, and showing an expulsive spiral belonging to a disk screen immediately above.

40 The different parts of the machine embodying my invention are held in position by a suitable framework. The preferable construction of frame consists of four upright square posts A, (Fig. 3,) which are held together near the bottom by four horizontal pieces, as A', and mortised into the upright pieces. The pieces all lie in the same horizontal plane. The upright posts are held together at the top by a square, independent 45 frame (Fig. 1), A², A², A², A², composed of four pieces A². These pieces A² are framed together independently of posts A, and are

held to the latter by screws or other suitable means. Within this framework and upheld thereby preferably in a manner hereinafter 55 described, is the screening apparatus, preferably constructed as follows:—The top plate or board B is provided with a central orifice B', for the admission to the screening apparatus of the material to be separated. On 60 the under side of plate B are the distributers B², B⁷, B¹⁰, B¹³, shown in Figs. 2^a, 2^b and 2^c. Immediately below these is a revolving screen C, as shown in Figs. 4 and 5^a.

Distributers B², B⁷, B¹⁰ and B¹³ are pivot- 65 ally secured to plate B. A convenient mode of securing these distributers to said plate B is by means of radial strips B², the distributers being pivotally fastened to the strips B², and the latter fixed to the plate B. All of 70 each series of distributers are connected by rings B⁴, B⁸, B¹¹ and B¹⁴, each of which is continuous. The movement of any particular ring in the line of its periphery will compel 75 all of the series connected to said ring to vibrate in unison. The means for sliding the ring in the direction of its length is prefer- 80 ably as shown in Fig. 2^a, and is as follows:—One of the distributers of each series carries a lug B⁵, to which is attached the operating 80 rod extending out beyond the edge of the plate B, in convenient reach for the operator. The rod operating series B² is designated by the character B⁶, that of series B⁷, by B⁹, of series B¹⁰ by B¹², and of B¹³ by B¹⁵. The con- 85 nection of a distributer to a ring is shown in Figs. 2^b and 3^c, in which B¹⁶ is a slotted plate suitably secured to the rod. Through the slot B¹⁷ of plate B¹⁶ passes a pin B¹⁸, firmly 90 secured in the distributer. Thus the motion 90 of the distributer operated by the said rod, is communicated to a ring and that of the ring to the distributers connected thereto. The distributers are preferably slotted to admit the rings. By pulling rod B⁶ to the limit of its 95 movement the whole of the series of distributers B² is thrown into the position shown in full lines in Fig. 2^a of the drawings. In the same way, the other series are thrown in the 100 positions shown by means of their respective operating rods. By pushing in the rods B⁶, B⁹, B¹² and B¹⁵, to their opposite limit of movement, all the series will be thrown in the position shown in dotted lines in series B¹³. It

is easily seen that these or any intermediate positions are easily secured by the operator. When desired, each series may be moved independently of the others and in this way the 5 distributors of one series may assume a position different from the other series, as the condition of the material to be separated requires.

Figs. 5^a, 5^b, 5^c and 5^d show the preferable 10 construction of a disk screen C; said screen is composed of a number of segments C', each a complete screen in itself. Segments are suitably secured together and to the hub C² as by screws C³. The said hub C² is provided 15 with a set screw C⁴, by means of which the disk C is secured to and rotated by a central shaft extending vertically through the machine and driven by suitable mechanism at the top, or bottom. The straight sides of each 20 segment are slotted as indicated by C⁵; said slots being recesses for the reception of the heads of tacks used in securing bolting or wire cloth to segment. Each segment of the disk C is covered with the same grade of wire 25 or bolting cloth by tacking it to the face of the periphery and hub portions of segment and by turning the cloth over the edges of the radial portions and driving tacks until their heads are within the recesses. The disk 30 C is secured to the vertical shaft, in a horizontal plane just below, and almost in contact with the lower edges of the distributors B³, B⁷, B¹⁰ and B¹². When the distributors are 35 set in the position as shown in Fig. 5^a, the disk C will be rotated in the direction of the arrow. The material passing down through the orifice B' of the plate B falls upon the central portion of the disk shaped screen C and thence by the force communicated to it 40 (said material) moves out from the center of the disk shaped screen toward its circumference. On its way out, it comes into contact with the distributors of the several series. When the distributors are in one position, 45 namely, that shown in solid lines in Fig. 2^a of the drawings, they retard the material to be separated in moving toward the periphery of the screen. When they are in the position shown in dotted lines in Fig. 2^a of the drawings, they assist the material being separated 50 in its passage over the disk shaped screen toward the periphery of the latter. When found necessary, one or more series may be arranged to retard, while one or more of the series may 55 at the same time hasten the movement of the material toward the periphery. By retarding the material, at any annular point on the disk shaped screen, the capacity of the machine for separating is increased, and it is especially desirable to retard the material to be 60 separated on that part of the disk shaped screen which is adjacent to its periphery, as it is here that the screen provides the largest surface. A further reason for retarding the 65 material near the periphery of the disk shaped screen is to counteract the increased tendency of the material at such point to move rapidly

leave the screen owing to the increased centrifugal force there present.

Attached to the under side of the periphery 70 of the disk shaped screen are several scrapers C⁶, which move in a circumferential trough D, Figs. 4 and 6, formed by the outside wall D' of the machine and an annular wall D³ 75 constituting the inner side or wall of the trough, extending upward near to the lower side of the rim of the screen without touching it, the bottom being the rim of a stationary skeleton wheel frame upon which the inner wall D³ is fastened, and gathers up the 80 material thrown therein from the peripheral edge of the disk shaped screen C and carries it to the point of exit. This point of exit is usually in the form of a chute D⁴, which carries off the coarsest material which, failing to 85 pass through the screen of the disk C, has been discharged from off of it into the trough D. The inner wall D³ of this trough is directly beneath the rim of the diskal screen C so that no material which passes through the 90 screen will fall in the trough and while it approaches near to the rim of the screen it does not touch the same, so the screen will be allowed to freely rotate. The bottom of this trough is formed by the rim of a stationary 95 skeleton wheel frame which is constructed with spokes or radial arms D⁵ and this rim. The skeleton wheel frame is fastened stationary on the periphery of its rim to the easing 100 of the machine while at its center is an opening through which the shaft S passes and in which it loosely revolves. Its radial arms, or 105 spokes are suitably fastened at the center with an opening to admit the shaft S. Attached to the lower side of these radial arms 110 or spokes of this skeleton wheel frame are series of distributors similar in construction and operation to those shown in Fig. 2^a. The upper side of each arm is sharpened to prevent the material from lodging thereon. 115

Fig. 7 illustrates a disk shaped screen E, similar in construction, except the grade of cloth, which is finer, to disk shaped screen C, and located in a horizontal plane, just underneath and almost touching the lower edges of 120 distributors of skeleton wheel frame D⁵, secured by set screw and rotated by shaft S. Connected to and with disk shaped screen E are scrapers E² and trough F, similar in construction to trough D.

Immediately underneath and attached to disk screen E is a collecting spiral E', which freely revolves in close proximity to a solid floor F' underneath it and also forming the floor of trough F. This spiral, as it revolves, 125 collects the material which has passed through the disk shaped screen E, and fallen on the floor F', and conveys it to a central orifice F² in the floor F'. The construction of this floor F' is exactly similar to that of the plate B, the central orifice F², distributors F³, underneath and all. Beneath these distributors F³ 130 is located another horizontal disk shaped screen G, (Fig. 4) with construction, location

of distributors F^3 above, and attachments to shaft S similar to those above it. It differs from screen E in that the grade of its cloth is still finer. Connected to and with this disk shaped screen G are scrapers G^2 , a trough H with its discharging spout H' , all similar to those above.

Attached to and revolved by disk shaped screen G is an expelling spiral G' , Figs. 4 and 8, the reverse of the preceding spiral E' . This spiral revolves freely over and in close proximity to the lowest floor H^2 of the machine, which floor is secured to the same outside walls as trough H . This spiral collects the material which has fallen through the disk shaped screen G upon the floor H^2 and conveys it from the center outward and discharges it through the opening H^3 in floor H^2 .

My machine is preferably constructed in four distinct sections, I, J, K and L, (Fig. 3) each independent of the others. The lower section L consists of bottom floor H^2 and trough H , with disk shaped screen G and spiral G' revolving immediately above them, and within outside wall H^4 , and outside wall and its connections H and H^2 all resting on A' of the framework. Section K consists of floor F' with its suspended distributors F^3 and trough F with disk shaped screen E and spiral E' revolving immediately above them, all within outside wall F^4 . Section K is suitably secured to posts A of framework, as by bolts A^3 , so as to allow of vertical adjustment of section K . The adjustment is for the purpose of regulating the distance between the disk shaped screen G and distributors F^3 . Section J consists of skeleton frame D^5 , its distributors D^6 , trough D , and disk shaped screen C within wall D' similarly attached and adjustable as section K . Section I consists of plate B with its various attachments B^2 to B^{19} inclusive. Built onto plate B is a frame B^{20} , fitting the inside of frame A^2 and secured to it with vertical adjustment by screws A^4 . The number of these sections or parts may be varied according to the desired number of grades of the material to be separated.

The mode in which my invention operates is, in general, as follows:—The material entering the machine through the orifice B' , falls upon the first screen C , as much as will pass through the screen C , the remainder being carried off by means of trough D and spout D^4 . The amount passing through screen C falls upon screen E , a portion passing through, the residue being carried off by trough F and spout F^6 . The portion passing through screen E falls on floor F^2 of F' through which it falls on screen G , is distributed over the same by distributors F^3 , a portion passing through screen G , the residue being discharged by trough H and spout H' . The portion falling through screen G falls on floor H^2 and is collected by spiral G' and discharged through orifice H^3 . The improve-

ments hereinbefore described will be found very valuable in separating all ground milling stock and grading and cleaning grain.

While the various features of my invention are preferably employed together, one or more of them may be used without the remainder, and in so far as applicable one or more of said features may be employed in connection with separating apparatus other than that herein specifically set forth as a whole.

What I claim as new and of my invention, and desire to secure by Letters Patent, is—

1. In a separating machine, two or more skeleton segments covered with suitable screening material suitably fastened together and mounted upon a vertical driving shaft and forming by their connection a skeleton segmental wheel substantially as and for the purposes specified.

2. In a separating machine, a rotating screen, one or more series of distributors, each series pivotally connected to the plate or equivalent portion of the framework above it and also pivotally connected to a ring, and means for sliding the ring around and changing the angle of the discharge in relation to the rotating of the disks, substantially as and for the purposes specified.

3. In a separating machine, the rotating screen, and one or more series of distributors, each series pivotally connected to the plate or equivalent portion of the framework above it, and also pivotally connected to a ring, one of the distributors being provided with an arm or stud B^5 connected to the reciprocating rod B^9 extended out, within reach of the operator, substantially as and for the purposes specified.

4. In a separating machine, the combination of the rotating screen and the upper plate provided with central orifice B' , through which material to be separated passes onto the screen, and having radial strips D^2 , and one or more series of distributors, said distributors being pivotally connected to the said strips and to the rings, and means for sliding the rings in the direction of the strips forward or backward, substantially as and for the purposes specified.

5. In a separating machine, the rotating screen above which is located one or more series of distributors, each series pivotally connected to the radial arms of a skeleton wheel above it, and also pivotally connected to a ring which may be reciprocated in the path of its circumference, by means substantially as described.

6. In a separating machine, one or more series of radial, reversible, distributors permanently pivoted in a horizontal plane to a plate or equivalent portion of the framework, a suitable distance above a rotating disk-shaped screen, to allow a suitable amount of stock on the screen to pass under the distributors, substantially as shown and described.

7. In a separating machine, a screening or

separating wheel, rotating in a horizontal plane by a vertical driving shaft composed of segments suitably fastened together, each of which has a groove, in the outer edges of its 5 radial arms to admit the heads of the tacks fastening suitable screening material with which it is independently clothed, substantially as shown and described.

8. In a separating machine, a skeleton 10 wheel frame formed by radial arms, or spokes and a rim, which is fastened stationary on the periphery of the rim to the casing of the machine and in a central opening of which the shaft loosely revolves substantially as 15 shown and described.

9. In a separating machine, a ring fastened upon the rim of the skeleton wheel, a suitable distance within its circumference under

the rim of the disk-shaped screen without touching the screen, to keep the material 20 which passes through the screen separate from that which passes over the screen, substantially as and for the purposes specified.

10. In a separating machine a ring fastened upon the plate, a suitable distance within 25 its circumference under the rim of the disk-shaped screen without touching the screen, to keep the material which passes through the screen separate from that which passes over the screen, substantially as and 30 for the purposes specified.

RILEY A. STUBBS.
